[57] CLAIM

The ornamental design for a branching tool for copper
pipes, as shown.

DESCRIPTION

FIG. 1 is a perspective view of a branching tool for
copper pipes showing my new design;
FIG. 2 is a rear elevation view thereof, the front eleva-
tion view being a mirror image thereof;
FIG. 3 is a top plan view thereof;
FIG. 4 is a bottom plan view thereof;
FIG. 5 is a left-side elevation view thereof; and
FIG. 6 is a right-side elevation view thereof.

FIG. 1

FIG. 2

FIG. 3

FIG. 4

FIG. 5

FIG. 6
